UNITED STATES PATENT OFFICE

EUGEN MANDLER, OF VIENNA, AUSTRIA, ASSIGNOR TO THE FIRM CLIMAX MOTOREN-WERKE UND SCHIFFSWERFT LINZ A. G., OF VIENNA, AUSTRIA

MULTICYLINDER INTERNAL COMBUSTION ENGINE

Application filed February 27, 1929, Serial No. 343,192, and in Austria November 6, 1928.

This invention relates to multi-cylinder internal combustion engines, especially to water-cooled two stroke cycle engines, the cylinders of which are connected together so 5 as to form one or more blocks. In such engines, the cylinders are usually directly connected together at their upper and lower ends, or they are connected together to form a rigid unit by a common cooling jacket. It 10 is also known, rigidly to connect all the cylinders of an engine by a common cylinder cover secured by means of bolts or the like. In such engines, the upper portions of the cylinders exposed to heat, bend, if highly 15 heated, since the expansions due to heat, especially those perpendicular to the cylinder axis, cannot freely develop on account of the connection between the several cylinders. It is obvious that leakage between the pistons 20 and the cylinders, a higher piston friction and other inconveniences will result from this curvature of the cylinders.

The object of the present invention therefore is to avoid the above inconveniences by 25 arranging the cylinders so that each of them together with its cylinder head stands freely with its upper portion exposed to heat. In connection therewith, an extremely simple and advantageous arrangement is obtained 30 by providing a common, but removable cooling jacket having the form of a cap which is put over the cylinders. This cooling jacket has joints with each of the cylinder heads, these joints being advantageously of circular 35 form. This arrangement renders separate cooling jackets for each cylinder or cylinder head superfluous and furthermore a very good cooling of the cylinder heads is obtained. After removing the cooling jacket, the upper 40 portions and the heads of all the cylinders are easily accessible for inspection or repair.

In the accompanying drawings, which illustrate one constructional form of the invention, by way of example: Fig. 1 is a longitudinal section and Fig. 2 a cross section through the engine.

Figure 3 is a perspective view of the upper part of one of the cylinders together with a portion of the cover of the common cooling jacket, Figure 4 shows the complete cover

with a portion broken away and Figure 5 shows a three-cylinder block and cooling jacket with the cover removed.

The cylinders *a* form one piece with the lower part *o* of the cooling jacket, but they stand freely with their upper portions, that is to say, above the openings of the air inlet port *n* and the exhaust port *l*. Also the cylinder heads *b* secured by means of bolts are not connected together. It is obvious that 55 each of the several cylinder heads may also form one piece with its cylinder. The cooling space is completed by a cap *c* having circular joints *d* with each cylinder head *b*. These joints, not being rigid, enable the cylinders to expand freely. For this purpose a little free radial play *h*, which is shown on an exaggerated scale in Figure 3 is provided between the cylinder heads *b* and the holes of the cap *c*, into which the heads enter, while 60 a flexibility of these joints in the direction of the cylinder axis is obtained by the interposed yielding joint rings *d*, made for instance of rubber or the like.

All the bores *f* for the fittings, such as 75 valves, nozzles and the ignition devices, are placed within the joint rings *d*. By these means the said bores do not pass the cooling water space, so that special joints are not necessary for them. Furthermore, the cap 80 *c* can be removed without removing the said fittings.

What I claim is:

1. In a multi-cylinder internal combustion engine of the two stroke cycle type, a cylinder block comprising a plurality of cylinders open at their upper ends and cast together in one piece, said cylinders having their upper ends exposed to heat extending freely, so as to be capable of expanding without constraint under the action of heat, and separate cylinder heads secured to the said cylinders, as and for the purposes set forth.

2. In a multi-cylinder internal combustion engine of the two stroke cycle type, a cylinder block comprising a plurality of cylinders, open at their upper ends, separate cylinder heads secured to the said cylinders, a common cooling water jacket removably secured to said cylinder block so as to extend over all 100
